UNITED STATES PATENT OFFICE.

SIDNEY HOLLANDER SONN, OF NEW YORK, N. Y.

NECKWEAR-HOLDER.

1,271,379.

Specification of Letters Patent. Patented July 2, 1918.

Application filed October 27, 1917. Serial No. 198,861.

To all whom it may concern:

Be it known that I, SIDNEY H. SONN, a citizen of the United States, and a resident of the city of New York, borough of Manhattan, in the county and State of New York, have invented a new and Improved Neckwear-Holder, of which the following is a full, clear, and exact description.

The object of the invention is to provide 10 a new and improved holder for four-in-hand and similar neckties, arranged to hold the neckwear neatly in position for displaying and examining purposes, to allow convenient removal of any one of the articles by the 15 dealer, and to prevent shifting of the holder, and the articles carried thereby, in a box or similar container.

In order to accomplish the desired result, 20 use is made of a flat piece of stiff sheet material provided at its head end with tapering sides and back flaps forming continuations of the tapering sides, and a tying means attached to one of the flaps and extending across the other flap and around the articles 25 held on the front and rear of the holder.

A practical embodiment of the invention is represented in the accompanying drawings forming a part of this specification, in which similar characters of reference indicate corresponding parts in all the views.

Figure 1 is a sectional side elevation of the neckwear holder on the line 1—1 of Fig. 2;

Fig. 2 is a plan view of the same with 35 the cover removed;

Fig. 3 is a plan view of the holder prior to folding; and

Fig. 4 is a cross section of the neckwear holder on the line 4—4 of Fig. 1.

The neckwear holder is arranged within 40 a box 10 having a removable case 11, and the holder consists essentially of a body 12 in the form of a piece of stiff sheet material such as cardboard and the like, the piece being approximately rectangular in shape and 45 provided near the foot end with a transversely extending crease 13 for forming an angular foot 14 resting on the bottom of the box 10 and abutting against the foot end 50 of the said box, as plainly indicated in Figs. 1, 2 and 4. The body 12 is provided with creases 15 and 16 to provide back flaps 17 and 18 bent onto the back of the body 12, the creases and the flaps extending approximately 55 from the middle of the sides of the body 12 to the head end thereof, as will be

readily understood by reference to Figs. 2 and 3. To the under side of one of the back flaps, as shown, the back flap 17, is secured one end of a tying band 20 together with a 60 retaining disk 21 held in place by an eyelet 22. The neckties 25 are superimposed and doubled up with the neckbands extending at the back of the body 12 and the end portions overlying the front of the said body 65 12. The main end portion has tapering sides corresponding to the tapering side portions of the body 12 and formed by the back flaps 17 and 18, as above explained. The tying band 20 is passed across the end 70 portions of the neckties and then around the back flap 18 and over the neckbands at the back of the body 12 to be then tied to the retaining disk 21 in the usual manner thus 75 securely holding the neckties in place on the body 12 of the holder. When the body 12 is in position in the box 10 and the foot 14 abuts against the foot end of the box 10 then the head end of the body 12 is a distance from the head end of the box 10 to 80 accommodate the bent portions of the superimposed neckties thus insuring a snug fitting of the holder and its neckties in the box 10. It will also be noticed that by having the 85 tapering sides at the body 12 the latter can be conveniently taken hold of on the upper narrow portion to permit of removing the holder from the box 10 and replacing it therein together with the neckties attached to the holder. By providing the foot 14 the 90 foot end of the body 12 is raised sufficiently above the bottom of the box 10 to accommodate the superimposed doubled-up neckbands of the neckties 25, and which neckbands present an aggregate thickness in excess 95 of that of the end portions of the neckties 25, as will be readily understood by reference to Fig. 1. It is understood that the back flaps 17 and 18 extend toward each other and engage the neckbands of the neckties to securely hold the neckbands in place at the back of the holder, it being understood that the tying band 20 after being fastened in place prevents the back flaps from accidentally opening and releasing the neckbands of the neckties. The back flaps 17 and 18 converge and their corners rest on the bottom of the box 10, as plainly indicated in Figs. 1 and 4, thus providing a support for the body 12 at the head end of the 100 box.

It will be noticed that by the arrangement

described the neckties are neatly held in position on the holder for displaying and examining purposes and the dealer can readily remove any one or all of the neckties on untying the band 20 to allow removal of the neckties from the holder.

It will also be noticed that the holder with the neckties thereon is prevented from accidentally shifting in the box 10 thus 10 preventing injury to the neckties by undue rubbing within the box and its cover.

The neckwear holder shown and described is very simple in construction and can be cheaply manufactured.

Having thus described my invention, I 15 claim as new and desire to secure by Letters Patent:-

1. A holder for neckwear and similar articles, comprising a body made of a flat piece 20 of stiff sheet material and provided at its head end with tapering sides and back flaps forming continuations of the tapering sides, and tying means attached to one of the flaps and extending across the other flap and 25 around the article held on the body of the holder.

2. A holder for neckwear and similar articles, comprising a piece of stiff sheet material of an approximately rectangular shape 30 over the head end of which are doubled up a number of neckties, the end portions extending on the front of the piece and the neckbands extending on the back of the piece, the said piece having tapering sides 35 conforming to the correspondingly tapering

sides of the main end portions of the neckties, and the said piece having back flaps forming integral continuations of the said tapering sides, the back flaps engaging the outermost of the said neckbands, and a tying 40 band and fastener secured on one of the said back flaps and extending across the other back flap and around the front and rear portions of the neckties.

3. In combination, a box having a removable cover, a necktie holder within the box and having a body made of a piece of sheet material provided with a foot resting on the bottom of the box and abutting against the foot end of the box, the other 45 end of the body piece terminating a distance from the head end of the box, the neckties being doubled up over the head end of the body sheet and extending over the front and rear thereof, the doubled up portions fitting 50 into the space between the head end of the body sheet and the head end of the box, the said body sheet having tapering side portions extending from the head of the body sheet to points intermediate the head and foot 55 ends of the body sheet, the said body sheet having integral back flaps forming continuations of the said tapering side portions and engaging the rear necktie portions, a tying band and a tying disk secured to one back 60 flap and extending across the other back flap and the necktie portions at the front and back of the body.

SIDNEY HOLLANDER SONN.
